A. L. HARRISON.
Lubricator for Steam-Engines.

No. 225,124.

Patented Mar. 2, 1880.

UNITED STATES PATENT OFFICE.

ANDREW L. HARRISON, OF BRISTOL, CONNECTICUT.

LUBRICATOR FOR STEAM-ENGINES.

SPECIFICATION forming part of Letters Patent No. 225,124, dated March 2, 1880.

Application filed August 20, 1879.

To all whom it may concern:

Be it known that I, ANDREW L. HARRISON, of the city of Bristol, in the county of Hartford and State of Connecticut, have invented 5 a new and useful Improvement in Lubricators for Steam-Engines, of which the following is a specification.

My improvements relate to apparatus for lubricating the cylinders and valves of steam- 10 engines wherein the lubricating material is forced out of a reservoir by pressure in regulated quantities to effect an automatic supply. I make use of a chamber for containing oil fitted with a flexible diaphragm, beneath which 15 diaphragm the pressure is applied to raise the same and force the oil out, the flow being regulated by a cock and the oil passing through a transparent chamber, which permits observation of the quantity passing. The diaphragm 20 is balanced by the steam-pressure, and the force to expel the oil is obtained by atmospheric pressure obtained by the use of a vacuum-chamber, or by the use of a water-column. The oil-chamber is filled by the exhaust ac- 25 tion beneath the diaphragm, obtained by connecting to the exhaust of the engine or by the vacuum-chamber before mentioned.

My invention consists in certain novel features of construction and combination, where- 30 by the operation is rendered uniform and reliable, which features will be described in connection with the accompanying drawings, and pointed out in the claims.

In the drawings, Figure 1 is a vertical sec- 35 tion of the lubricator. Fig. 2 is a side elevation of the same. Fig. 3 is a sectional plan view on line *xx*.

Similar letters of reference indicate corresponding parts. 40 The oil and pressure chamber A is formed by the two concave disks *aa*, which are bolted together upon a flanged ring, *b*. The flexible diaphragms *cc* are clamped by disks *a*, and are separated by the flange of ring *b*, so that 45 there is a space between them. A single dia- phragm might be used; but I prefer two, as shown, with the space between them filled with glycerine or other non-freezing liquid, such material, while elastic, forming a solid 50 partition between the diaphragms, which prevents unequal stretching and equalizes the

pressure upon the diaphragms. The dia- phragms are of india-rubber or other suitable material, and the space between them is to be filled through openings *a'* in ring *b*, which 55 openings will usually be closed by screw-plugs.

At the under side of chamber A is screwed a tube, *d*. Through a packing-nut, *d'*, in tube *d* passes a rod, *e*, the inner end of which is rigidly connected to the center of diaphragms 60 *c* by means of clamping-washers, with a thimble intervening between the diaphragms; and to the outer end of rod *e* is secured a loop, *e'*, by which the rod can be moved by hand to draw the diaphragms to the bottom 65 of chamber A.

On the lower end of tube *d* is screwed a short cylinder, *f*, having its lower end open, and upon rod *e* is a disk or head, *g*, which fits closely in *f*, and is provided with a cup-leather 70 or metallic packing to render it air-tight.

At the upper side of the chamber A is a pro- jection, to which is attached the oil cup or re- ceptacle *h*, and also the tube *i*, for the dis- charge of oil from chamber A. The cup *h* and 75 tube *i* communicate with the chamber A by separate passages, that are fitted with cocks *h'* and *i'*, respectively, whereby they may be closed and communication from chamber A to cup *h* or tube *i* cut off. 80

Upon the upper end of the tube *i* is secured the chamber *k*, the sides of which are made of glass or other transparent material. In the bottom of *k* is a small opening communicating with tube *i*, and in the top of *k* is an opening 85 to a tube, *k'*, and coupling to which is to be connected the pipe that leads to the parts to be lubricated. The chamber *k* is to be filled with glycerine.

To the under side of chamber A the pipes *l* 90 *m* are connected, so as to have communica- tion separately to the space beneath the dia- phragms *c*, and are fitted with cocks *n o*. The pipe *l* is to be connected to the exhaust of the engine when the lubricator is used in connec- 95 tion with condensing-engines, and the pipe *m* is to be connected to the steam-pipe from the boiler.

I have shown the pipes *l m* connected by elbows with vertical pipes *l' m'*, that pass 100 through the bracket *p*, to which the flanged ring *b* of chamber A is rigidly connected. The

pipes l m are fitted with union-couplings for connection to the exhaust and steam pipes. This connection permits attachment of the lubricator to the engine or to a wall, as desired, by screws passed through the bracket h , and the parts will be firmly sustained by the bracket. There is also a second exhaust-pipe, r , that opens into tube d and cylinder f , and is fitted with a pipe, r' , for connection with the exhaust of the engine. In pipe r is a two-way cock, s , for closing connection between the cylinder f and pipe r' and opening connection between cylinder f and the outer air through pipe r , or vice versa.

15 To charge the reservoir A with oil, the oil is first poured in the cup h , the cock h' opened to allow the oil to enter A , and the cock n also opened, so that the space beneath diaphragm c may be exhausted by pipe l , the diaphragm c drawn down thereby, and the oil drawn into A . The two-way cock s will at the same time be open to cut off the exhaust-pipe r and open the cylinder f to the outer air. The reservoir A being thus filled, the cocks $h' n$ are to be closed and s turned to connect the exhaust-pipe r with the cylinder f , and the cock o opened to admit steam by pipe m beneath the diaphragms. The diaphragms are balanced by the steam-pressure, and the cylinder being exhausted above the head g , the atmospheric pressure beneath g forces the rod e and diaphragms c upward, and the oil is forced through pipe i into the glycerine-chamber k in drops at more or less frequent intervals, or in a continuous stream, the flow being regulated by cock i' . The oil passes up through the glycerine to tube k , from whence it flows to the cylinder.

With high-pressure engines, instead of using the exhaust-cylinder f and atmospheric pressure to force the oil out, I make use of a column of water in the pipe m , which acts, by gravity, to overcome the steam balance on the diaphragm c and force out the oil.

40 45 In the pipe i is seated a check-valve, t , which closes when the reservoir A is being filled and prevents back flow by suction in case cock i' is open. The reservoir may also be filled by drawing down rod e by hand.

50 The vessel k being of glass and filled with a transparent material, the amount of oil passing may be seen and the flow regulated as desired. Glycerine in the said vessel is better than water, for the reasons that it will not freeze or become discolored by the oil, and may be used a long time without requiring renewal, while water loses its transparency by discoloration, and must be frequently renewed.

55 60 I am aware that it is not new, broadly, to feed oil to a journal by means of hydrostatic pressure; but

What I claim as new is—

1. In lubricators for steam-engines, the oil-reservoir A , divided by a single or double flexible diaphragm, c , having an outlet at its upper side to the parts to be lubricated, and fitted at its under side with connections for a steam or water column pipe, substantially as described and shown, and for the purposes set forth. 65

2. In lubricators for steam-engines, the combination, with oil-reservoir and pressure-chamber A and its diaphragm c , of the rod e , connected to diaphragm c , and provided at its outer end with the hand-loop e' , substantially as and for the purposes set forth. 75

3. In lubricators for steam-engines, the combination, with the oil-reservoir A , having a flexible diaphragm, c , and connecting beneath the diaphragm with the engine-exhaust, of the cup h , cock h' , and inlet-passage, substantially as and for the purposes specified. 80

4. In lubricators for steam-engines, the combination, with the oil and pressure chamber A , balanced diaphragm c , and rod e , of the exhaust chamber or cylinder f , head g , and exhaust-pipe r , substantially as and for the purpose described. 85

5. In lubricators for steam-engines wherein the oil passes through a transparent vessel containing a liquid, the use of glycerine in such transparent vessel, substantially as and for the purposes set forth. 90

6. In a lubricator for steam-engines, the combination, with an oil-reservoir having a diaphragm balanced by steam-pressure, of a vacuum-chamber, whereby atmospheric pressure is obtained upon the diaphragm to feed the oil to the cylinder or other parts to be lubricated, substantially as described and shown. 95 100

7. In lubricators, the combination, with the oil and pressure chamber A , of the diaphragm c , separated by an intervening space that is filled with glycerine or similar material, as and for the purposes specified. 105

8. In lubricators, the oil and pressure chamber A , formed of two concave disks, a , attached to the flanged ring b , substantially as and for the purposes set forth. 110

9. The combination, with the oil-reservoir A and its attached parts, of the bracket p , connected to the ring b of the reservoir A , and sustaining the steam and exhaust pipes, as shown and described. 115

10. As a means for connecting the cylinder f to the oil-reservoir A , the tube d , screwed to A , formed with a screw for cylinder f , and surrounding the packing-nut of the piston-rod, as described and shown.
